UNITED STATES PATENT OFFICE

NATHAN FABRICANT, OF CHICAGO, ILLINOIS

DESIGN FOR AN ELECTRIC-LIGHT BULB

Application filed November 27, 1929. Serial No. 33,573. Term of patent 14 years.

To all whom it may concern:

Be it known that I, NATHAN FABRICANT, a citizen of the United States of America, residing at Chicago, in the county of Cook and State of Illinois, have invented a new, original, and ornamental Design for Electric Light Bulbs, of which the following is a specification, reference being had to the accompanying drawings, forming a part thereof.

In the drawings:—

Figure 1 is a side view of a light bulb illustrating my new design.

Figure 2 is a top plan view of the same.

As shown in the drawing, the bulb has the general outline of an ornamented airship, and its ornamentation consists of translucent or non-transparent sections which are separated by transparent lines, the latter extending both longitudinally and circumferentially of the bulb.

I claim:—

The ornamental design for an electric light bulb, as shown and described.

NATHAN FABRICANT.
